Cleveland Crane & Engineering Company,
Wickliffe, Ohio, a corporation of Ohio

Application May 26, 1932, Serial No. 613,688

17 Claims. (Cl. 104—111)

This invention relates to couplings or connections for structural members such as beams, angles, channels and the like, and is particularly adapted for connecting the adjacent free ends of arch beams employed in an overhead carrier system and suspending or supporting the same from a suitable superstructure.

An object of the present invention resides in producing a coupling of the type referred to in which the overhead room or clearance required is reduced to a minimum, thus making the installation particularly adaptable in locations in which the question of head room is of primary importance.

15. Another object of the invention is to permit increased load capacity over former similar structures or couplings and at the same time producing a simplified construction.

Another object of the invention resides in providing a coupling which is flexibly suspended or supported from a hanger rod in a manner to permit the system to swing under the swaying action of the load as it traverses the beam.

Another object of the invention resides in producing a coupling of the type referred to which is simple in construction, efficient in purpose and inexpensive to manufacture.

Referring to the drawing:

Figure 1 is a side elevational view of a fragmentary portion of a carrier system showing the invention embodied therein.

Fig. 2 is a transverse sectional view taken on line 2—2 of Fig. 1.

Fig. 3 is a transverse sectional view taken on line 3—3 of Fig. 1.

Fig. 4 is a top plan view of a portion of the arch beam and the coupling embodying the invention.

The manner of connecting and supporting the adjacent free ends of the rails or arch beams employed in a monorail system has always been an important consideration in connection with the installation of such systems.

Limited head room in existing buildings, where an overhead system is to be erected, is usually of primary importance and in buildings erected to accommodate overhead systems the question of cost enters.

The present invention, therefore, resides in a supporting connection for the free adjacent ends of monorail track sections which permits installation where very little head room exists and which simplifies the construction and, therefore, lessens the expense in connection with the installation.

55. In the drawing 10 indicates sections of an arch

beam having their inner adjacent ends free, but shown in abutting relation at 11, although this is not necessary. The upper portion of the beams adjacent the ends are cut away to provide a space 12, while the webs of the beams are cut away to provide openings 13 which materially lighten the structure.

The lower portion of the beam structure comprises an inverted T rail which is welded to the adjacent portion of the web and along the connection therebetween the web of the rail has longitudinally extending integral beads 14. The upper surfaces of the flange 15 of the rail have raised treads 16 extending longitudinally along the outer edges thereof and are adapted to support the wheels of a carrier, not shown. The upper portion of the beam is provided with the usual flange 17, the inner ends of which terminate at the opening 12.

A pair of plates 18, preferably identical in form, are disposed upon the opposite sides of the webs of the beam 10 and extend between the flanges 15 and 17. A plurality of aligned openings are provided in the plates 18 and the webs to receive rivets or bolts 19 which secure the elements in assembled relation. The lower portions of the plates 18 have longitudinally extending corrugations 20 which cooperate with the beads 14 tending to properly align the plates 18 and at the same time provide the necessary reinforcing therefor.

Extending along the upper edges of the plates 18 are integral flanges 21 which project laterally and in opposite directions, as more clearly shown in Fig. 3, the outer edges of the flanges preferably terminating in the planes of the outer edges of the flanges 17 and being disposed beneath the flanges. The central portion of the plates 18 and the flanges 21 are offset at 22 and the offset portions are disposed within the opening 12 between the adjacent edges of the flanges 17. The ends of the flanges 21, which lie beneath the flanges 17, may be rounded as shown at 22' in Fig. 4.

Transversely aligned openings 23 are provided in the plates 18 having rounded upper portions which are cut out at 24 to provide flat surfaces 25. The plates 18 between the flat surfaces 25 and the flanges adjacent the offset portions 22 are offset to provide cooperating aligned recesses 26 extending transversely therebetween. A circular member 27 has a counterbore 28 in its upper side which receives the lower ends of the offset portions providing the recesses 26 and has an opening 29 which is in alignment with the said 55

- recesses 26. This circular member 27 may be welded or otherwise secured to the offset portions and the lower surface is preferably concave, as in Fig. 2.
- 5 A hanger rod 30 extends through said recesses 26 and said opening 29 and has a screw threaded end which receives a rocker nut 31 having a convex upper surface engageable with the concave surface on the member 27 to provide a swivel or 10 flexible connection therebetween. A lock or chuck nut 32 is also mounted upon the screw threaded end of the hanger rod 30 and provides for longitudinal adjustment of the hanger rod 30, as well as a securing means for the rocker nut 31.
- 15 The upper end of the hanger rod 30 has a head 33, the upper side being rounded or convex and is adapted to be supported from any suitable superstructure, so as to provide for a flexible or swivel connection therebetween.
- 20 In the drawing a preferred support is shown comprising a rail clamp 34 of U-shape in cross section and having flat surfaces 35 along its upper free ends which engage with the bottom of a beam flange 36. The clamp 34 has an opening 37 therein of larger diameter than the diameter of the hanger rod 30 which extends therethrough and the head engages the surface around the opening 37 to provide a swivel connection.
- 25 The clamp 34 has oppositely inclined lower surfaces 38 upon which are slidably mounted a pair of clips 38' adjustable by means of a rod 39 having its upper ends connected to members or 30 plates 40 welded or otherwise secured to the inner surfaces of the clips 38'. The clips 38' have bearing members 41 secured thereto which engage the upper surfaces of the beam flange 36 and, when the clips 38' are moved toward each other 35 by the rod 39, the flange is securely clamped between the bearing members 41 and the rail clamps 40 34.
- 35 While I have described the preferred embodiment of the invention, it is to be understood that 45 I am not to be limited thereto inasmuch as changes and modifications may be resorted to without departing from the spirit of the invention as defined in the appended claims.
- Having thus described my invention, I claim:
- 50 1. A device of the character described comprising a pair of supporting plates spaced apart in substantial parallelism and having laterally extending flanges at their upper portions, said plates being adapted to be connected to the adjacent ends of spaced members, said plates having aligned openings therethrough and co-operating recesses extending inwardly from said flanges and terminating at said openings, a hanger member having a portion disposed within 55 said recesses, and a connection between said plates and the adjacent end of said hanger member.
- 60 2. A device of the character described comprising a pair of supporting plates spaced apart in substantial parallelism and having laterally extending flanges at their upper portions, said plates being adapted to be connected to the adjacent ends of spaced members, said plates having aligned openings therethrough and co-operating recesses extending inwardly from said flanges and terminating at said openings, a hanger member extending through said recesses and having its adjacent end screw-threaded, and 65 70 screw-threaded means engageable with the screw-
- threaded end of said hanger member and providing a connection with said plates.
3. A device of the character described comprising a pair of supporting plates spaced apart in substantial parallelism and having laterally extending flanges at their upper portions, said plates being adapted to be connected to the adjacent ends of spaced members, said plates having aligned openings therethrough and co-operating recesses extending inwardly from said flanges and terminating at said openings, a hanger member extending through said recesses and having its adjacent end screw-threaded, a swivel connection between said plates and said hanger member, and a screw-threaded member engageable with the screw-threaded end of said hanger member and said connection. 5 10 15
4. A device of the character described comprising sectional track members having laterally extending wheel engaging flanges and webs connected thereto, the portions of said webs adjacent said flanges being in abutting relation and the other portions of said webs being in spaced relation, a member connected to the adjacent ends of said webs, and a hanger member having one end connected to said member at a location between the spaced portions of said webs. 20 25
5. A device of the character described comprising sectional track members having laterally extending wheel engaging flanges and webs connected thereto, the portions of said webs adjacent said flanges being in abutting relation and the other portions of said webs being in spaced relation, a member connected to the adjacent ends of said webs, and a hanger member having one end swivelly connected to said member at a location between the spaced portions of said webs. 30 35
6. A device of the character described comprising sectional track members having laterally extending wheel engaging flanges and webs connected thereto, the portions of said webs adjacent said flanges being in abutting relation and the other portions of said webs being in spaced relation, members disposed upon opposite sides of said track members and connected to the adjacent ends of said webs, and a hanger member having one end connected to said members at a location between the spaced portions of said webs. 40 45
7. A device of the character described comprising sectional track members having laterally extending wheel engaging flanges and webs connected thereto, the portions of said webs adjacent said flanges being in abutting relation and the other portions of said webs being in spaced relation, members disposed upon opposite sides of said track members and connected to the adjacent ends of said webs, and a hanger member having one end extending between said members and connected thereto at a location between the spaced portions of said webs. 50 55
8. A device of the character described comprising sectional track members having laterally extending wheel engaging flanges and webs connected thereto, the portions of said webs adjacent said flanges being in abutting relation and the other portions of said webs being in spaced relation, plates disposed upon opposite sides of said track members and connected to the adjacent ends of said webs, transversely aligned openings in said plates between the spaced portions of said webs, and a hanger member having one end extending between said plates through to said aligned openings and swivelly connected to said plates. 65 70 75

9. A device of the character described comprising sectional track members having laterally extending wheel engaging flanges and webs connected thereto, the portions of said webs adjacent said flanges being in abutting relation and the other portions of said webs being in spaced relation, plates disposed upon opposite sides of said track members and connected to the adjacent ends of said webs, transversely aligned openings in said plates between the spaced portions of said webs, said plates being provided with cooperating grooves intermediate the spaced portions of said webs and extending from said aligned openings outwardly, and a hanger member having one end extending through said cooperating grooves to said aligned openings and pivotally connected to said plates. 5
10. A device of the character described comprising sectional track members having upper and lower laterally extending flanges and connecting webs, the lower flanges and a portion of the webs being in abutting relation while the upper flanges and another portion of the webs are in spaced relation, a member connected to the adjacent ends of said webs, and a hanger member having one end connected to said member at a location between the spaced portions of said webs and flanges. 15
11. A device of the character described comprising sectional track members having upper and lower laterally extending flanges and connecting webs, the lower flanges and a portion of the webs being in abutting relation while the upper flanges and another portion of the webs are in spaced relation, plates upon opposite sides of said track members and connected to the adjacent ends of said webs, said plates having laterally extending flanges at their upper portions the opposite ends of which are adapted to underlie the adjacent portions of said upper flanges, and a hanger member having one end connected to said plates at a location between the spaced portions of said webs. 25
12. A device of the character described comprising sectional track members having upper and lower laterally extending flanges and connecting webs, the lower flanges and a portion of the webs being in abutting relation while the upper flanges and another portion of the webs are in spaced relation, plates upon opposite sides of said track members and connected to the adjacent ends of said webs, said plates having laterally extending flanges at their upper portions the opposite ends of which are adapted to underlie the adjacent portions of said upper flanges, said plates having transversely aligned openings and cooperating grooves intermediate the spaced portions of said webs, said grooves extending from said aligned openings outwardly, and a hanger member having one end extending through said 30
- grooves to said aligned openings and pivotally connected to said plates. 5
13. A device of the character described comprising a supporting member having a laterally extending flange and adapted to be connected to the adjacent ends of a pair of spaced members, a hanger member, and a connection between said supporting member and said hanger member located between the adjacent ends of the spaced members, said flange reenforcing said supporting member adjacent the connection between it and said hanger member. 10
14. A device of the character described comprising a supporting member having a laterally extending flange and adapted to be connected to the adjacent ends of a pair of spaced members, a hanger member, and a swivel connection between said supporting member and said hanger member and located between the adjacent ends of the spaced members, said flange reenforcing said supporting member adjacent its connection with the hanger member. 15
15. A device of the character described comprising a pair of supporting plates spaced apart in substantial parallelism and having laterally extending flanges at their upper portions, said plates being adapted to be connected to the adjacent ends of spaced members, a hanger member, and a connection between one end of said hanger member and said plates and located between the adjacent ends of the spaced members, said flanges reenforcing said plates adjacent the connection between them and said hanger member. 20
16. A device of the character described comprising a pair of supporting plates spaced apart in substantial parallelism and having laterally extending flanges at their upper portions, said plates being adapted to be connected to the adjacent ends of spaced members, a hanger member, and a swivel connection between one end of said hanger member and said plates and located between the adjacent ends of the spaced members, said flanges reenforcing said plates adjacent their connection with said hanger member. 25
17. A device of the character described comprising a pair of supporting plates spaced apart in substantial parallelism and having laterally extending flanges at their upper portions, said plates being adapted to be connected to the adjacent ends of spaced members, said plates being provided with cooperating recesses to provide an opening therebetween, a hanger member having one end disposed within said opening, and a connection between said plates and the adjacent end of said hanger member and located between the adjacent ends of the spaced members, said flanges reenforcing said plates adjacent their connection with said hanger member. 30
